Inventor.

Clive W. Lanphere
per Thos. S. Crane, Atty

UNITED STATES PATENT OFFICE.

CLIVE W. LANPHERE, OF BROOKLYN, NEW YORK.

DOORLOCK WITH AUTOMATIC INTERLOCKING BOLT.

Application filed May 25, 1922. Serial No. 563,645.

To all whom it may concern:

Be it known that I, CLIVE W. LANPHERE, a citizen of the United States, residing at Brooklyn, county of Kings, and State of New York, have invented certain new and useful Improvements in Doorlocks with Automatic Interlocking Belts, fully described and represented in the following specification, and the accompanying drawings, forming a part of the same.

This invention relates to that class of door-locks in which a bolt from a lock-casing operates to interlock with a guard upon a door, and the objects of the invention are:

First, to form such interlocking engagement with flat faces upon the lock-casing and the guard, so as to secure a very compact and neat appearance of the device;

Second, to obtain an automatic operation of an interlocking bolt when the lock is pressed toward the guard by the closing of the door. Such automatic locking of the door is secured whenever it is closed and prevents its reopening except by the use of a key or knob;

Third, to make the guard adjustable in relation to the lock-casing, to compensate for variations in their relative positions which arise from shrinkage in the wood-work or other causes; and,

Fourth, to reinforce the connection of the guard to the door-lock, so as to reduce the chance of prying the guard away from the lock by a "jimmy." A curved bolt is used rather than a straight one, because it permits the interlocking employed in the present invention, which operates to support the bolt at both ends within the lock-casing and also at several points within the keeper or guard.

These objects are all promoted by using a curved bolt which is proportioned to move out of the lock-case into a chamber upon a guard, through one aperture, and from another aperture to pass out of the said chamber and its end then engage an aperture in the lock-face. By this construction the bolt is wholly concealed in the casing when unlocked, and is strongly engaged with the guard when the door is closed.

The construction will be understood by reference to the annexed drawing, in which Fig. 1 shows a lock with one side removed

and the bolt retracted within the lock-case; Fig. 2 shows a lock with one side removed, 55 the adjacent guard in section, and the tongue of the bolt projected from the lock-case through the guard; Fig. 3 shows the face of the lock-case; Fig. 4 a side view of the entire lock-bolt; Fig. 5 an edge view of 60 the same; Fig. 6 shows a plan of the fixed portion of the guard; Fig. 7 shows the top-plate of the movable portion of the guard; Fig. 8 shows the edge of the door to which the lock-case is attached and the adjacent 65 door-jamb with the guard attached thereto, the guard being in cross section at the middle of its length; Fig. 8^a shows a view of the fixed portion of the guard viewed from the right-hand side of the guard shown in Fig. 70 8; Fig. 9 shows a view of the adjustable portion of the guard viewed from the right-hand side of the guard in Fig. 8; Fig. 10 is a cross section of the lock on line 10—10 in Fig. 2; Fig. 11 shows the lock-case with the 75 lid and all the movable parts removed; Fig. 12 is a longitudinal section of the lock-case taken on line 12—12 in Fig. 2; Fig. 13 shows the face of the lock-case with the tongue of the bolt partially projected, and 80 the beveled head of the detacher retracted within the face; and Fig. 14 shows an alternative means of securing the guard adjustably to the door-jamb.

The term "guard" where used herein covers any form of keeper or lock-plate adapted to cooperate with the curved locking-bolt in the manner described herein.

In Figs. 1 and 2, the bolt is shown in two positions, Fig. 1 showing the bolt retracted 85 in the casing, and Fig. 2 showing the bolt projected and engaged with the guard, as when the door 38 is closed and locked.

The bolt is shown detached in Fig. 4, having a body 20 with a tongue 21 extended 90 from its forward end, and a stem 22 extended from its rear end, to receive a tubular spiral spring 23.

A raceway for the body of the bolt is formed in the casing by ribs 24 upon the 100 side of the casing 19. The tongue is curved, as well as the body and stem, for a purpose that will be described, and an outlet aperture 25 is formed in the face-plate 26 through which the tongue is extended to engage the guard.

At the inner end of the raceway a seat or stop 32 for the spring 23 is provided, and the stem 22 passes through and extends beyond that seat when the bolt is retracted and the spring compressed.

Automatic control of bolt.

A detent 33 is connected to a detacher 35 and fits normally into a notch 34 in the edge of the body 20, to hold the bolt within the casing 19 while the door is open. At such time there is therefore no projection from the flat faces of the lock-case and the guard, excepting the outer end 36 of the detacher 35.

The detacher is formed as a bar 35 having a beveled head 36 which is projected from the face-plate 26 by a spring 37 on the shank of the bar, when the door is open.

The detent 33 is attached to the inner end of the bar 35, and the contact of the bevel-head with the guard withdraws the detent from the notch 34 and permits the spring 23 to propel the tongue 21 (from the aperture 25) into engagement with the guard. When thus engaged, the tongue embraces the metal between the apertures of the guard, and binds the guard firmly to the lock-case. (See Fig. 2.)

Guard construction.

The guard consists essentially of a box or chamber having a foot for attachment to the door-frame or jamb 38, and a face-plate 28 having two apertures 42 and 43 through which the tongue passes and its forward end then received in the inlet-aperture 31 on the face-plate 26 of the lock-case. Fig. 2 exhibits the parts thus arranged and shows the strong connection of the guard to the lock-casing.

The apertures in the guard correspond with those in the lock-face 26, and the tongue 21 passes through all four apertures when the door is closed. To strengthen the metal between the apertures in the guard, the said metal or post 39 may be thickened to a convex shape on its inner side, to fit the concave inner side of the tongue, so as to greatly strengthen the connection of those parts.

When the door is open, the parts of the lock occupy the positions shown in Fig. 1 but are automatically shifted into their operative positions by the contact of the detacher 36 with the lock-plate 28 upon the guard when the door is closed. To open the door thereafter, a locking-barrel 50 is provided in which a key may be inserted. Such barrel has an ear 51 projected toward the bolt-body which body has a lug 53 to engage the same, and retract the tongue of the bolt into the casing, by turning the key.

The lug and ear are provided respectively with a socket 52 (see Fig. 10) and a stud

54 (see Fig. 2) which engage one another when the lug is pressed toward the ear, and thus guide the bolt in a circular path and prevent the crowding of the bolt-body against the guide-ribs 24.

70

Compensation for shrinkage.

In case the woodwork shrinks, on which the lock-case or guard is secured, the guard would be so displaced that it would not admit the tongue to its apertures; and means is therefore needed to compensate for such shrinkage, or displacement from other causes.

In the present invention such means consists of an adjustable joint between the face and the foot of the guard.

The construction may be varied considerably, as shown in the drawings annexed, in which Figs. 7, 8 and 9 show one construction, and Fig. 14 another.

The constructions all show the guard made in two pieces, one secured to the wood-work and the other fastened thereto by adjustable means so as to set it nearer to the lock-case when required.

The simplest form of construction is shown in Fig. 14 where an angle-piece 41 is shown secured upon the corner of the door-jamb 55 and ribbed upon its outer side to fit ribs on the foot 40, upon which is formed a hollow box or chamber with lock-plate 50 upon its front side provided with apertures to permit the passage of the bolt-tongue through the guard, as shown in Figs. 2 and 13.

Where there is any displacement of the lock or door, it is evident that the lock-plate of this guard can be moved toward the face of the lock upon the door, and the initial condition thus be renewed at any time. The foot-plate is slotted to receive the screws 51² which hold the guard in place. The adjustment is effected by loosening the screws 51², and tightening them again after adjusting the guard at a suitable distance from the lock-case.

Figs. 7, 8 and 9 show a construction in which a flat lock-plate 38 is used which is attached to the jamb adjacent the edge of the door, and has flanges 43 and 50 adapted to fit within an open-sided box formed upon the foot-plate 40. This foot-plate is attached to the front side of the door-jamb and the adjustable lock-plate 28 is fastened to the edge of the jamb adjacent to the opposite edge of the door. The face of this lock-plate is shown in Fig. 9.

The space between the foot-piece and the lock-plate is made large enough for the passage of the bolt-tongue behind the post 39 through apertures 42 and 43 formed in the face of this lock-plate, as shown in Figs. 2 and 9.

The lock-plate 28 has its inner portion

130

fitted to lie upon the flat inner face of the door-jamb, and outside of such jamb is formed with longitudinal flanges, and end-flanges 51' which form a box upon the lock-plate upon its rear side. This box, as shown in Fig. 2, is fitted within a similar box formed on the foot-plate, thus closing the joint between the parts in all their adjustments.

10 A flange 44 is projected from the foot-piece opposite the outer side of the lock-plate, and a corresponding flange 43' is projected from the top of the lock-plate 28 and fitted beneath the flange 44 of the foot 15 to which it is secured by screws 45.

A row of holes 46 is shown in the flange 44 in Fig. 6, and three groups of tap-holes 47 are shown in the flange 43' (see Fig. 7) to operate with the screws 45 in the 20 flange 44 at different distances from the apertured face of the lock-plate 28.

With this construction the foot-piece of the guard is secured permanently upon the door-jamb, and the inner edge of the plate 25 28 is recessed into the inner side of the door-jamb to be flush therewith when the lock and guard are first applied. Three screws 45 are at such time fitted through the holes 47 in the three groups of Fig. 7 which are 30 nearest to the face of this lock-plate 28.

The door 41 is shown in Fig. 8 shrunk away from the adjacent face of the jamb a fraction of an inch, and the lock-plate 28 is shown moved outward from the foot-piece 35 40' a corresponding amount, to bring the lock-plate 28 close to the lock-case as at first.

To secure the lock-plate to the foot-piece in this new position, the screws 45 would be applied to a different series of holes in the 40 flanges 43' and 44. At the same time, packing-plates 38 are inserted between the inner edge of the lock-plate 28 and the side of the jamb, as shown in Fig. 8. The lock-plate of the guard is thus secured rigidly as at first, 45 although moved into a new position by the means described.

The lock-plate 28 is formed as shown in Fig. 2, with cheeks 50 at its ends, embracing cheeks 51' projected from the ends of the lock-plate 28, such construction closing the ends of the guard in any adjusted position of the lock-plate.

Packing-plates may be employed of any necessary thickness, and it is evident that the use of such an adjustable lock-plate and packing-plate permits the required adjustment without making any new screw-holes or loosening the grip of the foot-piece 40 upon the door-jamb. This is equally true of the constructions shown in Fig. 8 and Fig. 14.

Reference to Fig. 2 shows that the bolt-tongue 21 is interlocked with the guard and with the lock-casing, and any force applied 65 to strain the door from the door-jamb will

be effectually resisted, as the bolt can only be released by longitudinal movement, and any strain to pry the door and the guard apart is transverse to the line of the bolt and has no effect whatever in pushing it 70 lengthwise, which alone could release the interlocked parts.

To assure the normal interlocking of the bolt with the guard, one edge of the tongue 21 (Fig. 13) is tapered at 21' to permit 75 its entrance into the aperture 42 (Fig. 9) should the door not be fully closed when the bolt is projected, and to safeguard the movement of the bolt the notch 34 as shown in Fig. 1 is made of suitable depth so that 80 the detent will not be wholly withdrawn until the door is practically closed.

Having thus set forth the nature of the invention what is claimed herein is:

1. A door-lock having a bolt curved on an arc of a circle, a casing having means for projecting the bolt from its face and means for retracting said bolt, a guard formed in two parts, one having a foot to secure upon the door-jamb and the other 90 having a flange attached to the door-jamb and a plane face having apertures in the foot-piece, the foot-piece and the flange having overlapping parts provided with means for adjustment in different positions, and the packing-plates adapted to fit between the flange and the door-jamb when the said flange is adjusted as desired.

2. A door-lock having a bolt curved on an arc of a circle, a casing having means 100 for projecting the bolt from its face, a guard formed in two parts, one having a foot to secure upon the door-jamb and the other having a flange attached to the door-jamb and a plane face having apertures corresponding to the apertures in the foot-piece, the foot-piece and the flange having overlapping parts and said parts provided with three series of screw-holes adapted to hold 110 the flange upon the foot in several adjusted positions, and the packing-plates adapted to fit between the flange and the door-jamb when the said flange is adjusted as desired.

3. A door-lock having a circularly curved raceway therein, a similarly curved bolt having the body fitted to the said raceway, a tongue upon the body adapted to project from the lock-case and engage a suitable guard, a spring to project the tongue normally from the casing, a lock-barrel within 115 the casing, an ear projected from the bolt-body toward the lock-barrel, and a lug projected from the lock-barrel to retract the tongue into the casing when desired, and the lug and ear having respectively a socket 120 and a stud upon their opposed faces to maintain their relation to one another when in operation.

4. A door-lock having a casing with a circularly curved raceway therein, a simi- 130

- larly curved bolt having a body fitted mov- 65
ably to the raceway and provided with a notch, a tongue extended from the forward end of the body and a stem extended from its rear end, a spiral spring applied to the said stem and arranged to project the tongue normally from the casing, a detent to engage the notch, to oppose the locking movement of the tongue, means connected 10 with the detent and operated automatically upon the closing of the door to release the bolt and project the tongue to engage a suitable guard.
5. A door-lock having a casing with a circular raceway therein, a similarly curved bolt fitted to the curved raceway and provided with a notch, a spring to project one end of the bolt from the casing, a guard to interlock with the said bolt, a detent to 15 engage the notch in the bolt, a detacher connected directly with the detent and having its end projected from the casing when the detent is engaged, and pressed into the casing by the guard when the door is closed, and thus operating to withdraw the detent and cause the automatic release of the bolt, to engage the guard.
6. A lock having an arc-shaped bolt, a guideway for said bolt, means for projecting the bolt, a guard to interlock with the bolt, a detent to engage the bolt to hold the bolt retracted, such detent being directly connected to a detacher to disengage the detent from the bolt, and a lock-barrel having 20 means to retract the bolt.
7. A lock having an arc-shaped bolt, guides for the bolt, means for projecting the bolt, a guard to interlock with the bolt, a detent to engage the bolt to hold the bolt retracted, a detacher to disengage the detent from the bolt, and a lock-barrel having means to retract the bolt.
8. A lock having an arc-shaped bolt, said bolt having a stem projected from its rear end, and a spring adjusted to said stem.
9. A lock having an arc-shaped bolt composed of a tongue, a stem and an intermediate body portion and means for engaging said intermediate body portion to operate said bolt.
10. A lock having an arc-shaped bolt comprising an anterior tongue adapted to be projected from the lock, a spring behind said tongue for projecting said bolt and means for engaging said bolt to operate the same.
11. A lock having an arc-shaped bolt and a raceway, said bolt comprising a tongue, a stem and an intermediate body portion, the body-portion being fitted to said raceway, and means for engaging said intermediate body portion to operate said bolt.
12. A lock having an arc-shaped bolt comprising a tongue, an intermediate body por- 115
tion and a stem, a raceway in which said body-portion is slidable, a spring adjusted to said stem for projecting said bolt, and means for engaging said intermediate body portion to operate said bolt.
13. A lock having an arc-shaped bolt comprising a body portion, a rearwardly projecting stem, a forwardly projecting tongue, said tongue being of greater width than thickness and means for engaging said body portion to operate said bolt.
14. The combination of a guard having spaced apart openings in its face, a lock casing having an arcuate bolt adapted to be automatically projected from said casing to engage said openings, releaser means carried by said casing and adapted to engage the guard between said openings to automatically release said bolt, and means for projecting said bolt.
15. A lock comprising a casing, an arcuate bolt adapted to be automatically projected therefrom, means within the arc described by said bolt for automatically releasing said bolt when said releaser means engages a guard, said releaser means including means within said casing for holding the bolt retracted, and means for projecting said bolt when released.
16. A lock having a casing provided with an arc-shaped bolt, an arc-shaped spring fitted to project the bolt from the casing, and means to retract the bolt and means to retain it in the casing.
17. A lock having a casing provided with an arc-shaped bolt, an arc-shaped spring fitted to project the bolt from the casing and operating in the path of the bolt, and means to retract the bolt and means to retain it in the casing.
18. A lock having a bolt of arc-shape, means to retract the bolt, a detent to engage the bolt, a releaser to disengage the detent, a guard to engage the releaser and the bolt to cause the detent to engage said bolt, and means to project said releaser.
19. A lock having an arc-shaped bolt, said bolt having an arc-shaped spring adjusted to it, and means engaging said bolt for operating the same.
20. A lock having an arc-shaped bolt, and a detent to engage the bolt to hold the bolt retracted.
21. A lock having a casing, an arc-shaped bolt mounted on said casing, and a tumbler, means for interlocking the bolt and tumbler, and means for unlocking said bolt and tumbler.
22. A lock having an arc-shaped bolt and means directly engaging said bolt to hold the same retracted.
23. In a lock, a lock casing, a locking bolt mounted in said casing, a keeper comprising a portion adjustable toward and from said

lock casing, means for adjusting said portion, and means for securely locking said portion in its adjusted position.

24. A lock comprising an arc-shaped spring-projected bolt and a slideable detent for holding the bolt retracted.

25. A lock comprising a casing, an arcuate bolt, an arcuate spring to project said bolt, said bolt when projected engaging said casing at a plurality of points.

26. A lock comprising a casing, a bolt movable in an arcuate path, a stem associated with said bolt, a resilient member compressible by a movement of said bolt in one direction, and means for automatically releasing said member to move the bolt in another direction.

27. In a lock, the combination of a casing, an arcuate bolt, a helical spring, a

stem associated with said bolt and movable within said spring, means for holding said spring compressed, and means for automatically releasing said spring to move said bolt.

28. In a lock, the combination of a bolt comprising a tongue and a stem, a helical spring mounted upon said stem, means for moving said stem within said spring to accumulate energy, and means for releasing said energy to actuate said bolt.

29. A lock comprising a casing, an arc-bolt adapted to be projected from said casing, said bolt when projected engaging the casing at a plurality of points, and resilient means directly cooperating with said bolt for projecting the same.

In testimony whereof I have hereunto set my hand.

CLIVE W. LANPHERE.
